Karinear Induction Cooktop 30 inch. Date earliest reviewed Available on Amazon.com Mar. 31, 2021. <https://www.amazon.com/Karinear-Induction-Cooktop-Burners30-Stovetop/dp/B0BPM7F47L/> ref (Year: 2021).*Primary Examiner — Ricky Pham(74) *Attorney, Agent, or Firm* — CANTOR COLBURN LLP(57) **CLAIM**

The ornamental design for an induction range, as shown and described.

DESCRIPTION

FIG. 1 is a front perspective view of an induction range, showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof;

FIG. 8 is an enlarged view of the encircled portion '8' in FIG. 1;

FIG. 9 is an enlarged view of the encircled portion '9' in FIG. 1; and,

FIG. 10 is an enlarged view of the encircled portion '10' in FIG. 6.

The dot-dot-dash broken lines encircling enlargement portions of the design form no part of the claimed design.

The broken lines depicting portions of the Induction Range form no part of the claimed design.

1 Claim, 10 Drawing Sheets
